E. H. FAHRNEY

SNOWPLOW FEEDING MECHANISM

Filed April 30, 1925

FIG. 2.

FIG. 1

Inventor
Emery H. Fahrney
By *Y. R. Gelman, Atty.*

UNITED STATES PATENT OFFICE.

EMERY H. FAHRNEY, OF CHICAGO, ILLINOIS.

SNOWPLOW FEEDING MECHANISM.

Application filed April 30, 1925. Serial No. 26,911.

This invention relates in general to improvements in snow plows for removing snow from streets, roads or highways, and in which apparatus there is provided an impeller or 5 rotor for receiving and delivering the snow from the machine and a scoop like device for gathering and directing the snow to the impeller, the scoop and impeller being preferably arranged in an inclined position at 10 the forward end of the machine, and one of the objects of the invention is to provide improved means in connection with a scoop for assisting in conveying the snow to the impeller and for breaking up and disintegrating the snow as it is delivered to the impeller. 15

A further object is to provide in connection with the impeller improved means for feeding and delivering the snow to the impeller.

A further object is to provide an improved 20 apparatus of this character which will be of a simple, durable and compact construction and effective and efficient in operation.

To the attainment of these ends and the accomplishment of other new and useful objects as will appear, the invention consists in 25 the features of novelty in substantially the construction, combination and arrangement of the several parts hereinafter more fully described and claimed and shown in the accompanying drawing illustrating this invention, and in which

Figure 1 is a vertical sectional view as taken on line 1—1, Figure 2.

Figure 2 is a top plan view of the scoop and feeding mechanism.

Referring more particularly to the drawing the numeral 10 designates generally a scoop like device, the lower end of which preferably projects beyond a casing 11, and the scoop is of a width considerably greater than the diameter of an opening 12 in the bottom of the scoop and which opening has communication with the casing 11, forming the inlet thereto. Leading from the casing 11 is a discharge spout 13 through which the material which enters the casing is delivered.

Arranged within the casing 11 is a rotor 50 designated generally by the reference numeral 14, of any suitable construction, and this rotor is connected with a shaft 15 journaled in suitable bearings. The shaft has connected with it and on the outside of the casing a gear wheel 16 which meshes with a gear wheel 17 and which latter is connected with 55 a shaft 18 for rotation therewith, the shaft 18

receiving its motion from any suitable source (not shown).

Arranged within the scoop like device 10 is a deflector 19 which is arranged in the rear of the opening 12 and is shaped to partially encompass the opening. This deflector is preferably inclined to the bottom of the scoop and preferably extends entirely thereacross, and serves to assist in directing the snow into the opening 12.

A hood like closure 20 may be provided for a portion of the scoop and is preferably pivotally mounted as at 21 and serves as a means for preventing the snow from traveling out of the top of the scoop, and is pivotally mounted so that the snow will automatically control the rising thereof.

Arranged within the scoop, preferably adjacent the bottom thereof and extending longitudinally of the scoop are a plurality of 15 shafts 22 mounted in suitable bearings. Any number of these shafts may be provided and are connected so as to be driven from a single source of power preferably through the medium of sprocket chains 23 which pass over suitable sprocket wheels connected to the respective shafts. Motion may be imparted to these shafts through the medium of sprocket chains 24 which pass over sprocket wheels on certain of the shafts and also over a sprocket 80 wheel connected with a shaft 25, the latter being journaled in suitable bearings 26. The shaft 25 may receive its motion from any suitable source such as from the shaft 18 through the medium of a beveled gear 27 85 connected with the shaft 25, and which gear meshes with the gear 17.

Connected with the shafts 22 for rotation therewith are spiral blades or conveyors 28, one end of which preferably terminates adjacent the forward end of the scoop and the other end terminates adjacent the opening 12. Connected also with the shafts 22 for rotation therewith are a series of elements 29 which operate upon the snow for breaking up 90 or disintegrating it, and any number of these elements 29 may be provided.

A conveyor 30 preferably in the form of a spiral, is connected with the shaft 15 of the rotor 14 and projects into the scoop 10 with 95 its axis co-inciding with the axis of the rotor. This conveyor 30 may be of any desired diameter and length but is of a length to terminate within the scoop. As the rotor is operated the conveyor 30 also operates and forces 100

or feeds the snow which is within the scoop into or through the opening 12 in the bottom of the scoop to the rotor where it is caught and delivered through the discharge outlet 13.

With this improved construction it will be manifest that there will be a continuous feeding of the snow by the conveyors 28 and 30, and the elements 29 will operate upon the snow and any ice which may be present, as well as other foreign articles, to disintegrate or break up the same before being delivered to the rotor.

While the preferred form of the invention has been herein shown and described it is to be understood that various changes may be made in the details of construction and in the combination and arrangement of the several parts, within the scope of the claims, without departing from the spirit of this invention, and if desired any other suitable mechanism may be provided for rotating the shafts on which the conveyors 28 and elements 29 are mounted.

25 What is claimed as new is:—

1. A snow plow including a casing having an inlet and a discharge outlet, a rotor in the casing, a scoop like device discharging into the casing, a shaft adjacent and extending lengthwise of the bottom of the scoop and lengthwise of the direction of travel of the scoop, means for rotating the shaft, and a conveyor blade mounted upon the shaft and operating to feed the material through the scoop and along the bottom thereof to the inlet of the rotor casing.

2. A snow plow including a casing having an inlet and a discharge outlet, a rotor in the casing, a scoop like structure discharging into the casing, a shaft adjacent and extending lengthwise of the bottom of the scoop and of the direction of travel of the scoop, a conveyor mounted upon the shaft for conveying the material along the bottom of the scoop to the rotor casing, means also connected with the shaft and operating within the scoop to

disintegrate the material, and means for rotating the shaft.

3. A snow plow including a casing having a snow receiving inlet and a discharge outlet, a rotor in the casing, a scoop like structure discharging into the casing, a plurality of shafts adjacent and extending lengthwise of the bottom of the scoop and of the direction of travel of the scoop, conveying means mounted upon and individual to the shafts for conveying the material through the scoop along the bottom thereof into the casing, and means for rotating the shafts.

4. A snow plow including a casing having a snow receiving inlet and a discharge outlet, a rotor in the casing, a scoop like structure discharging into the casing, a plurality of shafts adjacent and extending lengthwise of the bottom of the scoop and of the direction of travel of the scoop, conveying means individual to and mounted upon the shafts for conveying the material through the scoop along the bottom thereof into the casing, additional means mounted upon the shafts for disintegrating the material, and means for rotating the shafts.

5. A snow plow including a casing having a snow receiving inlet and a discharge outlet, a rotor in the casing, a scoop like structure discharging into the casing, a plurality of shafts adjacent and extending lengthwise of the bottom of the scoop and of the direction of travel of the scoop, conveying means individual to and mounted upon the shafts for conveying the material through the scoop along the bottom thereof into the casing, additional means mounted upon the shafts for disintegrating the material, a conveyor mounted in line with the rotor for conveying the material into the rotor casing, and means for rotating the shafts.

In testimony whereof, I have signed my name to this specification, on this 24th day of April, 1925.

EMERY H. FAHRNEY.
